UNITED STATES PATENT OFFICE.

LOWELL H. KENYON, OF ALLEGHENY, PENNSYLVANIA.

CROSS-HEAD.

SPECIFICATION forming part of Letters Patent No. 409,290, dated August 20, 1889.

Application filed August 25, 1888. Serial No. 283,720. (No model.)

To all whom it may concern:

Be it known that I, LOWELL H. KENYON, a citizen of the United States, residing at Allegheny, in the county of Allegheny and State 5 of Pennsylvania, have invented certain new and useful Improvements in Cross-Heads; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to steam-engines, and has reference specially to the cross-head. The wear upon the cross-head gibbs is sustained by either the upper or the lower gib only, according to the direction in which the engine is 20 running. In a locomotive which runs for the most part in a forward direction the effect of the inclination of the connecting-rod is to cause the cross-head to press upward, when propelled by steam, when making either the 25 forward or the backward stroke. This brings the wear upon the upper gib. With the increase in boiler-pressures and the larger cylinders now coming into use, the pressure on the cross-head gibbs is becoming much greater 30 than heretofore, and consequently it is necessary to provide a larger wearing-surface to keep the friction down to the proper limit and prevent excessive wear and heating. A better mode of oiling the gibbs and guides is 35 also desirable. Both of these objects I have aimed to accomplish in my improved cross-head.

I make use of the ordinary two-bar guide, and provide the cross-head with the usual 40 gibbs, one bearing against the under side of the upper bar and the other bearing on top of the lower bar. I add to these another gib bearing against the under side of the lower guide-bar. This gives the cross-head three gibbs, 45 the top and bottom ones bearing against the under sides of their respective guide-bars and the middle one resting on top of the lower guide-bar. The top and bottom gibbs, however, sustain the thrust of the connecting-rod, 50 and as their combined bearing-surfaces are nearly double the area of the single gib ordi-

narily used, it is evident that the wear per square inch is reduced by nearly one-half and the friction is similarly greatly lessened. I also provide the gibbs and guides with oil holes 55 and chambers, whereby the oil is more evenly distributed, is fed from the top gib through to the bottom gib and thence to the cross-head pin, and the guides are kept oiled when the engine is at rest.

60 In the drawings, Figure 1 is a vertical longitudinal section of a two-bar guide and a cross-head embodying my improvements. Fig. 2 is a cross-section thereof through the cross-head pin, and the other figures are detail 65 views of the gibbs.

The same letters refer to the same parts in all the figures.

The guide consists of two bars A and B, 70 rectangular in cross-section and held in their relative positions in the usual manner. The cross-head C is provided with a socket for the piston-rod D and with two depending cheeks or jaws, between which the end of the connecting-rod E is held by the cross-head pin F, 75 as usual. The cross-head has also two upwardly-extending cheeks c c, which may be either cast integral with the cross-head or bolted to it, both constructions being common and well-known. These cheek-pieces inclose 80 the lower guide-bar B and terminate just below the upper guide-bar A, or may be made to extend up by either side of it. The gibbs G H I are fitted to lie snugly between the cheek-pieces c c, projecting at each end, where 85 they are provided with a lip or flange g h i, to prevent endwise movement in the cross-head. The top gib G and the middle gib H are separated by a block or a filling-piece K, preferably of cast-iron, which is held in place by 90 bolts k passed through the cheek-pieces c c.

On each gib G H is a transverse rib G' H', 95 which may project far enough from the backs of the gibbs to meet, in which case two blocks K would be necessary—one on each side of the ribs. As shown, however, the ribs do not meet, and the middle of the block K is cut away above and below to fit the ribs. The lips g h engage with the ends of the block K, as shown. The bottom gib I rests upon the 100 body of the cross-head, and at its middle is a deep transverse rib I', which projects down

through an aperture in the cross-head into the space between the depending cheeks that receive the connecting-rod.

In each of the ribs G' H' I' is formed a chamber for oil. The chamber in the gib G has a narrow mouth g' extending transverse of the gib. In its bottom are one or more holes g^2 , which register with similar holes k' passing through the block K, and communicate with the open oil-chamber formed in the rib H'. In the bottom of this oil-chamber are one or more holes h' , which allow the oil to escape and lubricate the upper surface of the lower guide-bar B. At suitable points in this guide-bar are drilled oilways b , through which the oil can pass to the bottom gib I. From this it enters a chamber in the rib I' through the narrow transverse mouth i' , escaping through a single hole i^2 , which is arranged to discharge the oil into the mouth of an oil-cup E', located upon the end of the connecting-rod E and supplying oil to the cross-head pin F.

In order to provide for oiling the guides immediately upon starting the engine, I form in the bearing-surfaces of the top and bottom gibs one or more shallow transverse depressions L. When the engine is at rest, the oil will collect in these depressions in sufficient quantity to lubricate the guides effectively when the engine is started.

The gibs are adjusted to bear evenly upon the guide-bars, and the wear is compensated for by means of shims slipped between gibs and the block K.

Suitable oil-holes may be formed through the cheek-pieces c c, to feed oil to the chambers and to the oil-cup E'.

I do not in this application make any claim to the lubricating devices hereinbefore described, they being reserved to form the subject-matter of a separate application.

Having thus described my invention, what I claim, and desire to secure by Letters Patent, is—

1. The combination, with a cross-head guide having two bars arranged one above the other, of a cross-head provided with three gibbs arranged one above the other in a vertical tier, two of them bearing against one of the bars and the third against the other bar, substantially as described.

2. The combination, with a two-bar guide, of a cross-head having three gibbs, two of which bear against the under sides of said bars, respectively, the third bearing upon the upper side of one of the bars, substantially for the purpose set forth.

3. The combination, with the guide-bars A and B, arranged one above the other, of the cross-head C, having the three gibbs G, H, and I, arranged and operating substantially as and for the purpose set forth.

In testimony whereof I affix my signature in presence of two witnesses.

LOWELL H. KENYON.
